UNITED STATES PATENT OFFICE.

LEO V. STOELTZLEN, OF ERIE, PENNSYLVANIA, ASSIGNOR TO GENERAL ELECTRIC COMPANY, A CORPORATION OF NEW YORK.

AIR STARTING MECHANISM FOR OIL-ENGINES.

1,087,406.

Specification of Letters Patent.

Patented Feb. 17, 1914.

Application filed September 30, 1912. Serial No. 723,049.

To all whom it may concern:

Be it known that I, LEO V. STOELTZLEN, a citizen of the United States, residing at Erie, county of Erie, State of Pennsylvania, have invented certain new and useful Improvements in Air Starting Mechanism for Oil-Engines, of which the following is a specification.

The present invention relates to air starting mechanism for internal combustion engines and particularly to that type of engine which depends for its operation on compressing the air within the cylinder to a temperature that is high enough to ignite the fuel injected by a blast of air. Such engines are commonly referred to as being of the constant pressure type. In starting an engine of this character it is necessary to temporarily disconnect, or render inoperative the mechanism for actuating the needle valve that controls the admission of fuel to the engine when the air starting valve is opened.

The object of my invention is to simplify and improve the means for starting such engines with an elastic fluid such as air under pressure.

In the accompanying drawing, which illustrates one of the embodiments of my invention, Figure 1 is a view, partly in elevation, of an engine fitted with my improved construction, and Figs. 2 and 3 are diagrammatic views illustrating the operation of the mechanism.

1 indicates the base of the engine, and 2 a cylinder mounted thereon. The engine may be provided with as many cylinders as is desired, some or all of which may be provided with starting valves. Mounted on top of each cylinder is a head, 3. In this head is a needle valve 4 that controls the admission of fuel to the combustion space of the cylinder in the ordinary manner, and 5 is a starting valve of any suitable construction.

Air under pressure is admitted to the valve chamber from any suitable source by the pipe 6. The needle valve is raised in normal operation by the lever 7, and is closed by the coiled compression spring 8,

the latter being mounted on a suitable frame, 9. The lever 7 is provided with a pivot that is made in the form of an eccentric 10, the latter being fastened on a shaft suitably supported in brackets, 11. On the 55 needle valve is a collar 12 that rests on the top of the lever when the latter is in its lowest operating position. The lever is actuated by an adjustable push rod 13 from the cam 14, the latter being mounted on a 60 cam shaft 15 which is driven by suitable gearing from the main shaft 16 of the engine. Under normal conditions the cam 14 raises the push rod, lever 7 and needle valve 4, every second revolution of the main shaft, 65 the air starting mechanism being cut out of service.

Referring now to the air starting mechanism, the starting valve 5 is normally held against its seat by a coiling compression 70 spring 17, the latter engaging the cylinder head at the bottom and a collar on the valve stem at the top. In order to depress the valve for the purpose of opening it a lever 18 is provided that is mounted on a suitable 75 fulcrum carried by the bracket 11. One end of the lever is provided with a roller 19 which when depressed engages the top of the starting valve stem and opens it against the action of the compression spring 17. The 80 lever is operated by a push rod 20 which is pivoted at its lower end to a lever 21. This lever is pivotally mounted on a bell crank lever 22. The stud or pivot 22 therefor is carried by the frame of the engine. The 85 right hand end of the lever 21 is provided with a roller 23 that under certain conditions is adapted to engage the small cam 24 mounted on the cam shaft 15. The bell crank lever 22 is actuated by a link 25, arm 90 26 and a handle 27, said arm and handle being mounted on the pivot 28, which is carried by the frame of the engine. The handle is provided with a spring pressed latch 29 that is adapted to enter one or the other of 95 the notches 30 formed in the fixed segmental plate 31. In order to limit the downward movement of the rod 20 it is provided with a collar 32 that engages some part of the engine frame.

Referring to Figs. 2 and 3, the operation of the invention will be described. As shown in Fig. 2, the lever 7 is in engagement with the collar 12 on the needle valve. 5 When it is raised by the action of the cam 14 and push rod 13 it will open the needle valve and permit fuel under blast pressure to enter the combustion space of the cylinder the starting valve in the mean while being idle. Assuming now that the engine is 10 idle and that it is desired to start it. The engine is first turned over by a bar or other means to its starting position. The handle 27 is then swung to the left as is shown in Fig. 3. This causes the roller 23 on lever 21 15 to be moved into engagement with the small cam 24 and said roller acts to move the lever 21 on its fulcrum whereby the rod 20 is pushed upward carrying with it the lever 18. 20 As a result of this the roller 19 depresses the starting valve 5 and admits air under high pressure to the cylinder. It will be noted that the fuel valve lever 7 has been depressed so that it no longer engages with 25 the collar 12 on the needle valve. This is brought about by reason of the turning of its eccentric pivot 10 which is rigidly fastened to the shaft 18^a and lever 18, the latter being moved by the rod 20. Under these 30 conditions the engine will start as an air engine and the cam 24 will cause the starting valve 5 to be opened and closed at the proper times during each complete cycle of operation. In other words in the present 35 engine, the air starting valve will be opened every second stroke while the needle valve 4 remains idle. As soon as the engine has acquired sufficient momentum the handle 27 is thrown to the right, the position shown in 40 Figs. 1 and 2, after which the engine operates in the ordinary manner, the starting valve 5 remaining closed.

My improved mechanism has the advantage of being easy to construct, is composed 45 of simple parts that are not liable to get out of order and which are accessible so that they may be readily adjusted to give the exact lengths of movement required. It also has the important advantage that when the 50 engine is operating in its normal manner the starting valve actuating means is idle thereby reducing wear on the parts and avoiding the movement of all parts unnecessary to normal working.

55 My invention is equally applicable to two cycle as well as to four cycle engines by properly arranging the valve actuating cams.

In accordance with the provisions of the 60 patent statutes, I have described the principle of operation of my invention, together with the apparatus which I now consider to represent the best embodiment thereof; but I desire to have it understood that the

apparatus shown is only illustrative, and that the invention can be carried out by other means.

What I claim as new and desire to secure by Letters Patent of the United States, is:—

1. An internal combustion engine having a fuel and a starting valve, in combination with a lever and cam shaft for normally actuating the fuel valve, a lever for actuating the starting valve that is normally idle, a fulcrum that is common to both levers and a device for turning the fulcrum to simultaneously move the starting valve lever into operative relation with respect to the cam shaft and render the fuel valve lever inoperative. 80

2. An internal combustion engine having a fuel and a starting valve, in combination with a lever for operating the fuel valve, a rotary cam shaft for normally vibrating the lever, a pair of connected levers for actuating the starting valve, said levers being normally inactive, a fulcrum that is common to the fuel valve lever and to one of said pair, and means for turning the fulcrum to render the fuel valve lever inoperative and move one of said pair of levers into operative relation with respect to the cam shaft. 90

3. An internal combustion engine having a fuel valve, and a starting valve, in combination with a pivoted lever, a rotary cam shaft for vibrating the lever to cause it to open and close the fuel valve under normal conditions, a pair of connected levers for actuating the starting valve, a pivot for one of the levers, means for adjusting said pivot to move the lever into and out of operative relation with respect to the cam shaft, and a device moved by said means for changing the position of the fulcrum of the fuel valve 105 lever to render it inoperative. 95

4. An internal combustion engine having a fuel valve and a starting valve, in combination with a pivoted fuel valve lever, a cam shaft for vibrating the lever to open 110 and close the valve, a lever system for opening the starting valve that is normally inoperative, and a means for simultaneously moving the fulcrum of the fuel valve lever and lever system to cut the fuel valve out of 115 operation and the starting valve into operation.

5. An internal combustion engine having a fuel valve and a starting valve, in combination with a pivoted fuel valve lever, a cam shaft for vibrating it to open and close the valve, a starting valve lever, a second lever connected therewith, and a means which moves the second lever into the path of a cam on the shaft, moves the starting 125 valve lever to open its valve and changes the position of the pivot of the fuel valve lever to prevent it from actuating its valve. 120

6. An internal combustion engine having
a fuel valve and a starting valve, in com-
bination with a fuel valve lever, a cam shaft
for actuating it, an adjustable pivot for said
lever, a starting valve, a lever for actuating
it and also adjusting the said pivot, a second
lever linked thereto, an adjustable pivot for
the second lever, and a handle for changing
the position of the pivot of the second lever
10 and causing the starting valve lever to

change the position of the fulcrum of the
fuel valve lever.

In witness whereof, I have hereunto set
my hand this twenty seventh day of Septem-
ber, 1912.

LEO V. STOELTZLEN.
